UNITED STATES PATENT OFFICE.

CALVIN VOORHIS, OF NEW YORK, N. Y., ASSIGNOR TO HIMSELF, ABRAHAM SHENFIELD, AND HARRY L. SHENFIELD, OF SAME PLACE.

PANTALOONS-SUPPORTER.

SPECIFICATION forming part of Letters Patent No. 391,726, dated October 23, 1888.

Application filed September 29, 1887. Serial No. 251,007. (No model.)

To all whom it may concern:

Be it known that I, CALVIN VOORHIS, of the city and State of New York, have invented an Improvement in Pantaloons-Supporters, of 5 which the following is a specification.

Waistbands have been made for the upper parts of pants with upwardly-projecting ears at the sides of the front portion and at the middle of the back, and to these the suspenders have been hooked; but the tension of the 10 suspenders tends to make the side portions of the pants over the hips loose and uncomfortable and to pull the pants unduly at the crotch, especially when the person is seated.

15 The object of my invention is to distribute the strain uniformly at the top of the pants, to afford additional security of connection between the pants and the suspenders, and to prevent inconvenience from buttons breaking 20 off.

In the drawings, Figure 1 is a perspective view of the upper portion of the pants, and Fig. 2 is a similar view of the suspenders for the different points of attachment.

25 The flaps or ears *a* are of a suitable shape to be attached along their lower edges to the top part of the pants at the insides of the band and in about the ordinary positions for the suspender-buttons both in front and at the 30 back, and in each of these flaps there is a button-hole, 2, adapted to receive the button 3 upon the suspender, and, the fabric of the suspender being usually much stronger than that of the cloth of the pants, the buttons are not liable to become detached. I also provide a second button, 4, and button-hole 5 as an additional security at each suspender-end, and

place the button on the flap and the button-hole in the suspender-end, such suspender-end being double in order to receive the two sets of fastenings. This gives the additional convenience of being able to support the drawers by either buttons upon them or button-holes or loops as usually provided. 40

I have shown the buttons 4 below the button-holes 2 at the front of the pants and above them at the back parts of the pants. 45

I do not limit myself to any particular character of suspender-webbing or suspender-ends, but prefer to have the ends of double or folded 50 webbing, as shown, to form two tips, one of which has a button-hole and the other a button.

By having a button and button-hole together at each point of connection on the pants there is less risk of the parts breaking or becoming 55 injured than where a single button or button-hole is used, because there is double strength; and if two button-holes were used together at one place one would be liable to tear or extend into the other, and no benefit would be 60 derived therefrom.

I claim as my invention—

The suspender-ends, each formed of a piece of webbing folded and having a button and button-hole and attached to the main suspender-straps, in combination with the flaps, each having a button-hole and button and attached to the pants, substantially as set forth. 65

Signed by me this 23d day of September, 1887.

CALVIN VOORHIS.
